(57) **CLAIM**

The ornamental design for a bottle, as shown and described.

DESCRIPTION

FIG. 1 is an upper perspective view of a first embodiment of a bottle showing our new design;

FIG. 2 is a front view thereof;

FIG. 3 is a rear view thereof;

FIG. 4 is a right side view thereof, the left side view being identical;

FIG. 5 is a top view thereof;

FIG. 6 is a bottom view thereof;

FIG. 7 is a lower perspective view thereof;

FIG. 8 is an upper perspective view of a second embodiment of a bottle showing our new design;

FIG. 9 is a front view thereof;

FIG. 10 is a rear view thereof;

FIG. 11 is a right side view thereof, the left side view being identical;

FIG. 12 is a top view thereof;

FIG. 13 is a bottom view thereof; and,

FIG. 14 is a lower perspective view thereof.

The broken lines in the drawing illustrate portions of the bottle that form no part of the claimed design.

1 Claim, 10 Drawing Sheets
